DOOR FASTENER

Martin Jensen, Penn Yan, N. Y.

Application February 7, 1933. Serial No. 655,645

11 Claims. (Cl. 292—104)

This invention relates to improvements in door fastening devices and pertains particularly to a device wherein there is a hook carried by the door and a keeper carried by the adjacent door frame.

The primary object of the present invention is to provide a door fastening device having an adjustment feature whereby the use of the fastener is permitted for securely locking the door even though it may be impossible to completely close the door as a result of warping of the same or for other reasons.

Another object of the invention is to provide a device of the above described character which is designed to have a padlock or other locking means associated therewith whereby the fastener may be secured against operation as desired.

A still further object of the invention is to provide a door fastener employing a hook and a keeper, wherein the keeper includes a swingable bar with which the hook is connected, which bar carries a plurality of elements adjustable thereon to facilitate the altering of the point of connection of the hook therewith, whereby differences in the distance between the point of connection of the hook with the door and the point of connection of the keeper with the door frame due to dampness or warping of the door or due to other causes, may be compensated for.

The invention will be best understood from a consideration of the following detailed description taken in connection with the accompanying drawing forming part of this specification, with the understanding, however, that the invention is not confined to any strict conformity with the showing of the drawing but may be changed or modified so long as such changes or modifications mark no material departure from the salient features of the invention as expressed in the appended claims.

In the drawing:

Figure 1 is a horizontal sectional view through a portion of a door and an adjacent frame showing partially in section and partially in elevation, the keeper embodying the present invention;

Figure 2 is a view in front elevation of the keeper structure showing the same in applied position;

Figure 3 is a sectional view taken substantially upon the line 3—3 of Figure 1.

Referring now more particularly to the drawing wherein like numerals of reference indicate corresponding parts throughout the several views, the numerals 1 and 2 indicate respectively

a portion of a door and a portion of the adjacent jamb therefor.

The device embodying the present invention is in two units one of which, indicated generally by the numeral 3, may be referred to, as an entirety, as the hook, while the other which is indicated as a whole by the numeral 4, may be referred to, as an entirety, as the keeper.

The hook 3 comprises a flat bar 5 which has an aperture 6 at one end in which is engaged the eye 7 of a bolt 8. This bolt is secured in the door 1 in the manner shown and the bar 5 swings freely from the eye 7. At the other end of the bar 5 there is pivotally secured thereto by means of the rivet 9, the flat hook element 10 which has the bill 11 formed at the free end as shown.

The keeper 4 comprises a channel-like body having a back wall 12 and spaced parallel edge walls 13 which are at right angles to the back wall as shown. At one end of this channel member the side walls are provided with the longitudinally extending slots 14, while at the opposite end the side walls are connected by the pin 15.

The channel member of the keeper is secured horizontally to the door frame 2 in the manner shown, that is, with its back wall 12 against the frame and the side walls 13 extending forwardly therefrom. The pin 15 will then be vertically disposed as shown.

The pin 15 is extended through one end of and is pivotally connected with a keeper bar 16 and the other end of this bar is turned back upon itself to form the bill portion 17 of a relatively deep hook which is indicated as a whole by the numeral 18.

This keeper bar as shown is of greater length than the channel in which it is mounted and it is adapted to be swung into the channel with the bill portion 17 of the hook abutting the rear wall, so that the area between the bill and the body of the hook or the bar 16 is in vertical alignment with the openings 14 in the walls 13. This permits of the extension into the hook 18 behind the bill 17 thereof, of the shiftable latch pin 19 which is disposed vertically between the walls 13 and which has its ends extended through the openings 14 in the manner illustrated. The ends of this latch pin are headed as shown and interposed between each head and the adjacent wall 13 is a washer 20 which slides against the adjacent wall 13 to facilitate the movement of the pin. As shown in Figure 1 the extent of the slots or openings 14 in the walls

13 is such that the latch pin 19 may be shifted sufficiently to permit the hook bill 17 to swing outwardly clear of the latch pin so that the keeper bar 16 may be swung out of the channel member.

10 Adjacent the end of the keeper bar which is pivotally connected with the pin 15 there is resiliently and removably attached to the keeper bar the split sleeve 21 which serves as a spacer for groups of washer elements 22 and 23. The washer element 22 at the forward end of the sleeve is permanently retained in this position, while at the other end of the sleeve a number of the washer elements are held in the manner illustrated.

15 In the operation of the present door fastener all of the washer elements except the element 22 are normally retained at the end of the keeper bar adjacent the pivot pin 15 and when the door is closed the keeper bar 16 is swung outwardly to extend away from the channel member in which it is mounted and the bill 11 of the pivoted end portion 10 of the hook unit 3 is engaged over the portion of the keeper bar which is partially surrounded by the sleeve 21. The keeper bar may then be swung back into the channel member to the position where the latch pin 19 may be shifted into the hook 18. This will then hold the units 3 and 4 together. If 20 the door is to be locked then a suitable padlock such as is indicated at 24 may be used by passing the staple portion 25 through the opening 14 in the lower wall 13 of the keeper unit channel member in the end of the opening nearest the door. This will prevent movement of the latch pin 19 back the necessary distance to free the bill 17 of the hook at the end of the keeper bar. In the event that the door cannot be closed 25 entirely so that the hook unit will be virtually shortened this alteration in the relative positions of the units may be compensated for by removing the sleeve 21 and slipping one or two or more of the washers 23 forwardly against the washer 22 and then replacing the sleeve 21 to hold the washers in the positions to which they have been moved. The bill end of the hook unit 30 may then be engaged with the keeper bar 16 at a point closer to the pivot pin 15 of the keeper bar and the keeper bar may be moved all the way in to the position in which it is shown in 35 Figure 1.

40 In addition to the foregoing it will be readily seen that the means of adjusting the relative positions of the units 3 and 4 may also be employed in the event that they are not properly located by the mechanic attaching them to the door and jamb.

45 Having thus described the invention, what is claimed is:—

1. A door latch, comprising a hook, a keeper including a swinging bar with which the hook is connected, and means adjustable longitudinally of and on the bar to compensate for changes in 50 the relative positions of the hook and keeper to permit proper coupling of the same together.

2. A door latch, comprising a hook, a keeper including a swinging bar with which the hook is connected, means on the bar adjustable to compensate for changes in the relative positions of the hook and keeper to permit proper coupling of the same together, and means carried by the keeper for securing the bar against movement.

3. A door latch, comprising a hook, a keeper 55 unit consisting of a channel member, a bar piv-

otally secured at one end within the channel member and adjacent an end of the latter whereby its other free end may be swung out of the member, the said bar when in operative position extending longitudinally of the channel and having its pivoted end nearest the hook, and means for securing the free end of the bar within the channel, the said hook being adapted to engage the bar to be held thereby.

4. A door latch, comprising a hook, a keeper unit consisting of a channel member, a bar pivotally secured at one end within the channel member and adjacent an end of the latter, the said bar when in operative position extending longitudinally of the channel and having its pivoted end nearest the hook, means for securing the free end of the bar within the channel, the said hook being adapted to engage the bar to be held thereby, and means adjustable on and longitudinally of the bar whereby the point of connection of the hook therewith may be adjusted.

5. A door latch, comprising a hook member, a bar pivotally mounted at one end to swing upon a vertical axis, the said hook having a bill for connection across the bar and the free end of the bar being swingable away from the hook when the bar is moved to operative position, means for securing the bar against movement, and means for adjusting the point of connection of the hook with the bar.

6. A door latch, comprising a hook member, a bar pivotally mounted at one end to swing upon a vertical axis, the said hook being adapted for detachable connection with the bar and the pivoted end of the bar being nearest the hook when the bar is in operative position, means for securing the bar against movement, and means for adjusting the point of connection of the hook with the bar comprising a plurality of shiftable elements slidably mounted upon the bar and a spacer partially encircling the bar for retaining the said elements in a selected position.

7. A door latch, comprising a hook divided into two pivotally connected portions, one of said portions being reverted to form a hook bill, keeper means comprising a bar pivotally mounted at one end, with which said hook bill engages when in operative position, said bar having its free end directed away from the hook when in operative position, and shiftable means upon the bar whereby the point of connection of the hook bill with the bar may be regulated.

8. A door latch, comprising a hook member, a keeper consisting of a channel-like member, a bar pivotally secured at one end in one end of the channel-like member to swing upon a vertical axis, the other end of the bar being reverted to form a hook bill which when the bar is in operative position has its tip disposed within the channel, the said channel member having its side walls slotted at the end adjacent the hook bill, and a pin connecting said walls and having its ends slidably extended through the slots thereof, said pin member being movable in the slots of said walls to position between the bar and the hook bill to retain the latter in operative position, said slots providing means, after moving said pin, for the engagement of a locking element with the channel around the bar.

9. A door latch, comprising a hook member, a keeper consisting of a channel-like member, a bar pivotally secured at one end in one end of

- the channel-like member to swing upon a vertical axis, the other end of the bar being reverted to form a hook bill which when the bar is in operative position has its tip disposed within 5 the channel, the said channel member having its side walls slotted at the end adjacent the hook bill, a pin connecting said walls and having its ends slidably extended through the slots thereof, said pin member being adapted to 10 enter between the bar and the hook bill to retain the latter in operative position, and means on the bar for adjusting the point of connection of the first mentioned hook with the bar. 10. A door latch, comprising a hook member, 15 a keeper consisting of a channel-like member, a bar pivotally secured at one end in one end of the channel-like member to swing upon a vertical axis, the other end of the bar being reverted to form a hook bill which when the bar is in operative position has its tip disposed within the channel, the said channel member having its side walls slotted at the end adjacent the hook bill, a 20 pin connecting said walls and having its ends slidably extended through the slots thereof, said 25 pin member being adapted to enter between the bar and the hook bill to retain the latter in oper- 30
- ative position, and means on the bar for adjusting the point of connection of the first mentioned hook with the bar, comprising a plurality of elements shiftably mounted upon the bar, a member carried by the bar and constituting a stop for the movement of said elements longitudinally thereof and a split spacer sleeve removably carried by the bar between said stop member and the pivoted end of the bar for retaining said movable members in a selected 35 position. 11. A door latch, comprising a swingingly mounted hook having a bill at its free end which when in operative position is substantially horizontally disposed, a bar member designed to be pivotally supported adjacent the hook to swing on a vertical axis, said bar when in operative position being disposed substantially at right angles with the body to which the hook is attached and said hook bill being designed to engage over the 40 bar, elements movable on the bar for shifting the point of connection of the bill therewith, and an element removably mounted on the bar for retaining said shiftable elements in adjusted 45 position thereon. 50
